UNITED STATES PATENT OFFICE

108,177

DESIGN FOR A RANGE

Rudolph Hoffman, Rocky River, Ohio, assignor to American Stove Company, St. Louis, Mo., a corporation of New Jersey

Application October 28, 1937, Serial No. 72,485

Term of patent 14 years

To all whom it may concern:

Be it known that I, Rudolph Hoffman, a citizen of the United States, residing in Rocky River, county of Cuyahoga, and State of Ohio, have invented a new, original, and ornamental Design for Ranges, of which the following is a specification, reference being had therein to the accompanying drawing forming a part thereof.

The figure of the drawing is a perspective view of a design for a range.

The appearance of that end of the range not shown in the drawing is the same as that end which appears in the drawing.

The dominant features of my design reside in the portions shown in full lines.

I claim:

The ornamental design for a range as shown and described.

RUDOLPH HOFFMAN.
